United States Patent Office.

ASA T. WOOLSEY, OF SANDUSKY, OHIO.

Letters Patent No. 70,146, dated October 22, 1867.

IMPROVED IRONING-TABLE.

The Schedule referred to in these Letters Patent and making part of the same.

TO ALL WHOM IT MAY CONCERN:

Be it known that I, A. T. Woolsey, of Sandusky, in the county of Erie, and State of Ohio, have invented certain new and useful improvements in Ironing-Tables; and I do hereby declare that the following is a full and complete description of the same, reference being had to the accompanying drawings, making a part of this specification, in which—

Figure 1 is a perspective view.

Figure 2 is a detached section that will be referred to in the description.

Like letters of reference refer to like parts in the views.

This table consists of the rack A, or basket and ironing-board B. This basket is constructed in the following manner: B' are standards. Extending from one end of this rack to the other is the cross-piece C, pivoted at x to the standards, as shown. Secured to these standards near the top are the side pieces or boards D D, one on each side. Connected to and passing through the pieces C D D, in the manner shown in the drawing, is the cord E, thus forming a basket for holding the clothes. On the top of the standards are placed the boards or strips a a', one at each end. These strips hold the basket firm and steady while using the board, and are also for the board to rest upon. The said board B is pivoted to the strip a', as shown a" in fig. 2, which is an under side view of the board and strip. I is the handle of the board, in which are cut one or more grooves, c c. This is for the cord d to catch in, and thus support the opposite end of the board, which may be raised more or less, as desired. The board is pivoted to the strip a', as stated, so as to allow it to be turned round to or from the person ironing, or off from the basket for the purpose of taking out or putting clothes in the basket.

The basket is also convenient in ironing anything large, as skirts, to hold them while being ironed, and thus prevent them from brushing on the floor and getting dusted and stepped on. When the table is not to be used the board can be removed and the basket closed, as indicated by the dotted lines K, fig. 1, thus taking up very little room, and making a very convenient ironing-board and basket.

What I claim as my improvement, and desire to secure by Letters Patent, is—

The standards B', cross-bar C, and cord E, in combination with the board B, having a horizontal and vertical adjustment, substantially as and for the purpose set forth,
